SPARK PLUG CONNECTION

John M. Oldham, Pleasant Ridge, Mich., assignor
to L. A. Young, Detroit, Mich.

Application May 25, 1938, Serial No. 209,905

2 Claims. (Cl. 173—269)

This invention relates to a spark plug connection and has particularly to do with a device for forming a connection between wires from a distributor of an internal combustion engine and the spark plugs of said engine.

Many attempts have been made to provide a less expensive spark plug connection than is now generally used. The main difficulty has been to achieve a device which would stand up against the constant vibration to which these parts are subjected and still maintain a proper contact.

An object of the present invention is to provide an inexpensive means for providing a spark plug contact which will not break down under constant vibration or under the rough usage to which it is subjected by mechanics, etc.

A further object is to provide a spark plug connection which may be easily connected and disconnected innumerable times without affecting the efficiency of the contacts.

A further object is to provide a spark plug connection which needs no soldered or welded joint with the lead wire and which will bend resiliently without being injured.

Other objects and features of the invention having to do with details of construction thereof, will be further brought out in the following specification and claims.

In the drawing:

Fig. 1 is a side view of the connection showing the spark plug and lead wire.

Fig. 2 is a section taken on the lines 2—2 of Fig. 1.

Fig. 3 is a side view of the lead wire and connecting coil.

Figs. 4, 5 and 6 are transverse sections taken on the lines 4—4, 5—5 and 6—6, respectively, of Fig. 1.

Fig. 7 illustrates the coil connection in a flexed position.

Referring to the drawing, a spark plug 10 is shown in Fig. 1. A substantially cylindrical metal cap 11 is shown on the top of the spark plug 10, this cap being provided with an annular bulged or rounded portion 12.

A lead wire 13 is attached at one end to a distributor (not shown), and is arranged to be attached at the other end to the spark plug 10. This wire is preferably formed of a number of copper strands and is insulated with a relatively heavy insulation 14. The insulation is preferably formed of a substantial thickness of rubber 15 around the wire 13 with a fabric or other type of covering 16. The rubber 15 is preferred soft and pliable.

To form the connection between the cap 11 and the wire, I have provided a closely wound coil 17. The lower portion 18 of the coil, as shown on the drawing, is adapted to telescope over the cap 11 and to be firmly held thereon. I preferably form the lower portion of this coil with an internal dimension slightly smaller than the external dimensions of the cap 11. The lower portion of the coil is also provided with an annular concavity on its internal surface to correspond with the annular convexity 12 on the cap 11. By reason of this formation of the two parts, the coil 17 will be firmly held on the cap 11 thereof. It may be slipped on or pulled off of the cap 11 with comparative ease due to the fact that the coil spring will expand.

The upper portion 19 of the coil 17 is adapted to receive the terminal end of the lead wire 13 including the insulation. The upper portion 19 of the coil is also provided with a slightly smaller internal diameter than the external diameter of the insulation in order to provide a snug fit when the coil is slipped over the end of the insulated wire. The coil 17 is preferably formed of a spring steel which is coated with zinc plating or copper plating to carry the electric current and to prevent rusting. Steel is not an excellent electrical conductor as are zinc, silver and copper. I have found that plating the coil with one of these better conducting metals makes it an excellent conductor for the spark plug connection.

The upper end 20 of the wire which forms the coil is bent diametrically of the coil and pressed through the rubber insulation 15 to the lead wire 13. When the end of the wire 20 is cut off, it is usually formed in a sharp point and this point will be forced through the strands of the lead wire 13. A positive contact is thus assured between the parts.

In view of the fact that a relatively high voltage passes through the lead wire to the spark plug, it is unnecessary to solder the connection between the wire 13 and the end 20. Even though a gap is left in this contact, it will operate successfully. The rubber 15 will close tightly around the end 20 to seal the contact between the end 20 and the wire 13 from moisture.

I claim:

1. An electrical connection for use on a spark plug for an internal combustion engine comprising a cap having a substantially cylindrical shape with an annular convexity at one portion thereof, a lead wire to be connected to said plug, insulation on said lead wire, and a coil of spring wire for electrically and physically connecting 50

- said cap and said lead wire, one end of said coil being dimensioned to slip over said cap and having an annular concavity on its inner surface to receive the convex portion of said cap in locking relation, the other end of said coil being dimensioned to receive the end of said insulated lead wire, one end of the wire forming said coil being bent diametrically of said coil and driven into said insulation to contact said lead wire, said end being retained in said position by the resilience of said coil.
5. An electrical connection for use on a spark plug for an internal combustion engine comprising a cap member having an annular restricted portion therein, a lead wire to be connected to
10. An electrical connection for use on a spark plug for an internal combustion engine comprising a cap member having an annular restricted portion therein, a lead wire to be connected to
15. An electrical connection for use on a spark plug for an internal combustion engine comprising a cap member having an annular restricted portion therein, a lead wire to be connected to

said plug, insulation on said lead wire, and a coil of spring wire for electrically and physically connecting said cap member and said lead wire, one end of said coil being dimensioned slightly smaller than said cap member whereby when said end is slipped over said cap, certain winds in said coil will be received by said restricted portion to provide a resilient, yet locked, connection with said cap, the other end of said coil being adapted to receive and retain insulation surrounding said lead wire and having an end portion bent diametrically of said coil and pressed into said insulation to contact said lead wire.

JOHN M. OLDHAM. 15
